S. CHRISTENSEN

FINGERING MECHANISM FOR CONTRABASS VIOLS

Filed Feb. 4, 1919

UNITED STATES PATENT OFFICE.

SØREN CHRISTENSEN, OF COPENHAGEN, DENMARK.

FINGERING MECHANISM FOR CONTRABASS VIOLS.

Application filed February 4, 1919. Serial No. 275,004.

To all whom it may concern:

Be it known that I, SØREN CHRISTENSEN, musician, a subject of the King of Denmark, residing at Copenhagen, Hobrogade 9, Denmark,

5 have invented a Fingering Mechanism for Contrabass Viols (for which I have filed an application in Germany January 2, 1918, No. 313,951, of July 28, 1919), of which the following is a specification.

10 This invention relates to contrabass viols and more particularly to key operated means for holding the strings to the finger board.

A feature of this invention is the provision of means for controlling the strings of a contrabass, said means being fixed relatively to the finger board so that the strings will be held thereto at the exact place necessary to give the proper note when the bow is 20 drawn across the strings. This insures that a note will sound exactly the same each time it is played. An instrument made in accordance with the present invention is advantageous over those now in use since ordinarily the inexactitude of the position of the player's finger on the finger board causes slight variations in the sound of the note.

Other features and advantages will hereinafter appear.

30 In the accompanying drawings:

Fig. 1 is a side view of an instrument constructed in accordance with the present invention.

Fig. 2 is a front view of the same.

35 Fig. 3 is a detail showing a guiding bridge for the key levers.

Fig. 4 is a detail showing one of the fretting members for the higher notes, the support and means for operating said fretting member being also shown.

40 Fig. 5 is a detail showing the same as Fig. 4 only in connection with a lower note.

Fig. 6 is a detail showing the yoke for holding the fretting members.

45 The finger board *a* and the strings *b* of an instrument constructed in accordance with the present invention are the same as those found in the contrabass viols now in use, with the exception that the side of the finger board is provided with bars *c* which are so shaped as to form longitudinal grooves for receiving various parts of the string operating mechanism.

50 The finger pieces or keys and the fretting fingers operated thereby are so arranged as

to produce notes at semi-tone intervals, the fretting fingers being disposed along the finger board at suitable intervals for this purpose.

The key levers *e* are pivotally mounted at 60 *d* on extensions of the side bars *c*, and are provided with keys *f*, *f'*, *f''* and *f'''*, at their free ends. The key levers are provided with arms *o* (Fig. 5) each pivotally connected to a damper yoke *l* so that when a key *f* is depressed by the player the yoke *l* associated therewith will be caused to hold all the strings to the finger board at a particular place thereon. For this purpose the yoke *l* is pivoted, as by studs *k*, to clamps *j* mounted on and held to the side bars *c* and so arranged as to swing about said pivots downwardly against the strings. The yoke *l* has a crosspiece *m* directly beneath which is provided the fretting member *n* which preferably comprises a leathern band which closely simulates the finger of the human hand and thus does not unduly wear the strings.

To limit and guide the movement of the keys there is provided a comb *g* in the spaces 80 *h* between the teeth of which the key levers extend and by the sides of which they are guided. The comb *g* is mounted on the grooved side bars *c*. The keys are held in normal position by springs *i*.

85 From the foregoing it will be clear that by properly manipulating the keys and drawing the bow across the proper string all semi-tones within the range of the instrument can be sounded.

90 The higher notes which are only played on the two strings to the right in Fig. 2 are controlled by similar devices, the keys *s* being the same as the keys *f* and the arms *z* being the same as the arms *o*. The fretting fingers however are not exactly the same for the reason that it is not necessary for the higher notes to fret the strings at the left of Fig. 2. Therefore, instead of the yoke *l* which is provided for the lower notes there 100 is provided an arm *x* pivotally mounted at *w* in an arm *v* having grooves to be received by the bar *c*. At the free end of the arm *x* there is provided a fretting member *y* which is pivoted to the arm *x*. The arm *z* is 105 pivoted to the arm *x*.

The arms *z* and *o* are adjustable on the key levers *r* and *e* respectively.

110 Since the clamps *j* and the arm *v* and also the arms *o* and *z* can be arranged along

the finger board in any desired position, the exact tone desired can always be produced.

The device of this invention can be attached to any contrabass by merely attaching the bars *c* to the sides of the finger board.

Variations may be resorted to within the scope of this invention and portions of the 10 improvements may be used without others.

I claim as my invention:

1. In a viol, the combination with a finger-board; of strings extending over said finger-board; and a plurality of fretting 15 fingers set at definite intervals along said finger-board; and keys, one for each fretting finger, and each remote from its fretting finger, said keys being located substantially midway of the ends of the finger- 20 board.

2. In a viol, the combination with a finger-board; of strings extending over said finger-board; a plurality of fretting fingers each comprising a yoke adjustably mounted 25 on the finger-board, and a leathern member for engaging the strings; and key operated means for moving said yoke to cause said leathern member to firmly press the strings upon the finger-board and comprising 30 keys located substantially midway of the ends of the finger-board, said keys being remote from their associated fretting fingers.

3. A fretting device for the finger-board 35 of a viol comprising keys placed at the middle of the finger-board; levers, one for each key, arranged in groups with one group extending upwardly and the other downwardly from the keys; and a trans- 40 verse rod associated with each group of levers and remote from the keys for pivotally supporting the levers.

4. A fretting device for the finger-board of a viol according to claim 3 in which

there are fretting fingers pivotally mounted 45 at the sides of the finger-board and in which there are means connecting each of said fretting fingers to the one of said levers with which it is associated.

5. A fretting device for the finger-board 50 of a viol according to claim 3 in which there are fretting fingers pivotally mounted on brackets carried by a side of the finger-board and in which there are means connecting each of said fretting fingers to the 55 one of said levers with which it is associated.

6. A fretting device for the finger-board of a viol according to claim 3 in which there are fretting fingers pivotally supported at 60 points between the keys and the supporting rods and in which there are combs located between the keys and the fretting fingers for guiding the levers.

7. A fretting device for the finger-board 65 of a viol according to claim 3 in which there are fretting fingers, brackets secured to and extending upwardly from the finger-board and on which a fretting finger is pivotally mounted, and an arm engaging said fretting 70 finger and mounted on the one of said levers with which the fretting finger is associated.

8. In a contrabass viol, the combination with a finger-board and a body portion; of strings extending over said finger-board; a plurality of fretting fingers set at definite intervals along said finger-board; and keys, one for each fretting finger, located substantially midway of the end of the finger-board in position to be engaged by the fingers of the player while the latter's arm rests on the body portion of the viol, said keys being remote from their associated 80 fretting fingers.

SØREN CHRISTENSEN.
